(57) **CLAIM**

The ornamental design for a holder for soldering iron as shown and described.

DESCRIPTION

FIG. 1 is a first perspective view of a holder for soldering iron showing our new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the holder for soldering iron in which the design is embodied that are not considered part of the claimed design.

The dot-dash lines show a boundary between the claimed design and unclaimed portions.
